UNITED STATES PATENT OFFICE.

TOKUJIRO HASHIMOTO, OF TOKYO, JAPAN.

COSMETIC.

No Drawing.

Application filed April 10, 1925. Serial No. 22,195.

This invention relates to an improved cosmetic and the process of producing the same.

One of the objects of the invention is to provide a cosmetic which, when applied to the skin of the face, will form a soft thin film possessing the properties of an antiseptic and will be soothing, the film-like coating, when dry, permitting of application of face powder and other cosmetics in a more ready and convenient manner than has heretofore been possible and likewise permitting the face powder or the like to remain for a longer period of time, as it is not in direct contact with the skin.

The cosmetic embodying the invention contains the following ingredients in substantially the proportions stated:

Bengal isinglass agar 1 part.

20 Boric acid solution (1% strength) 300 to 500 parts.

Solution of gloiopeltis furcata .15 parts in 10 parts of water.

Hexamethylenetetramine .01 part.

25 Benzoate of lithium or sodium .3 parts.

Lanolin in alcoholic solution approximately 3 parts.

In preparing the cosmetic, one part of agar or Bengal isinglass is mixed with from 300 to 500 parts of a one percent solution of boric acid and heat is applied and the solution placed under a pressure of approximately two atmospheres. This is done to reduce coagulation of the Bengal isinglass, and after this solution has been prepared, there is added thereto a solution of gloiopeltis furcata of a strength of .15 parts in ten parts of water and a mixture of .01 part of hexamethylenetetramine and .3 parts of 35 benzoate of lithium or sodium, together with a small amount of alcoholic solution of lanolin, and, if desired, any suitable perfume, heat being applied to the whole mixture and the mixture being thoroughly stirred and, if desired, at this time there may be added a small quantity of peroxide of hydrogen or other similar germicide. In preparing the solution of Bengal isinglass, the solution obtained is capable of forming a 40 very thin and soft film on the skin of the

face and likewise, the solution prevents decomposition of the hexamethylenetetramine, which is of importance as the antiseptic properties of this ingredient are, therefore, left unimpaired whereas the ingredient 55 might otherwise decompose, producing formaline and ammonia, which substances would have an irritating effect on the skin. Likewise, the benzoate of lithium or sodium assists in preventing deterioration of the 60 hexamethylenetetramine.

The gloiopeltis furcata and the lanolin serve to nourish the skin and have a soothing effect.

The cosmetic is applied to the skin of the 65 face and permitted to dry and will form a thin and soft film-like coating which is substantially invisible and over which powder may be applied or other cosmetics applied without the same coming in direct contact with the skin.

Having thus described the invention, what I claim is:

1. A substantially noncoagulative nonirritating cosmetic comprising an intimate mixture of Bengal isinglass agar in a solution of boric acid heated under pressure and a solution of gloiopeltis furcata, hexamethylenetetramine, benzoate of lithium, and an alcoholic solution of lanolin which when applied to the skin will form a thin soft dry film.

2. The process of preparing a cosmetic which comprises forming a slightly acid solution of Bengal isinglass agar, heating the 85 solution under a pressure of approximately two atmospheres to prevent coagulation, adding to the solution a solution of gloiopeltis furcata, hexamethylenetetramine, benzoate of lithium, and an alcoholic solution of 90 lanolin.

3. The process of preparing a cosmetic which consists in dissolving Bengal isinglass agar in a heated slightly acid solution under pressure and adding to the solution a small 95 quantity of hexamethylenetetramine.

In testimony whereof I hereunto affix my signature.

TOKUJIRO HASHIMOTO.
